UNITED STATES PATENT OFFICE

MARCUS A. HIRSCHL, OF CHICAGO, ILLINOIS

CANDLE

Application filed March 11, 1931. Serial No. 521,863.

This invention relates to improvements in candles and, more especially, a candle made of paraffin, wax, tallow, or the like.

The principal feature of my invention is the making of the lower end of the candle so that it can be readily reduced in diameter to adapt it to fit the desired candle holder. The end may be originally made of a diameter as great as the largest candle holder and then it can be reduced as desired to fit any candle holder.

Other features and advantages of my invention will appear more fully as I proceed with my specification.

In that form of device embodying the features of my invention shown in the accompanying drawings—

Figure 1 is a view in side elevation; Fig. 2 is a view taken as indicated by the line 2—2 of Fig. 1; Fig. 3 is a view similar to Fig. 1 showing how the strip at the lower end of the candle is unwound to reduce its diameter; and Fig. 4 is a view similar to Fig. 3 showing the end of the strip torn off and the diameter of the candle reduced.

As shown in the drawings, 10 indicates a candle of the ordinary form. Imbedded in the candle in the lower end is a roll of a strip of flexible sheet material 11. I have found, for example, that paper may serve the purpose. After the candle is made, portions of this strip may be unwound and torn off to reduce the diameter of the lower end of the candle, as desired.

I have found that if paper is used for the strip, such as news print paper, it becomes impregnated with the paraffin or other material of which the candle is made and the layers of the roll stick together to a certain extent so that the lower end of the candle is not materially weakened by having this roll of paper imbedded in it. The impregnation of the paraffin or tallow also keeps the paper from unwinding. It is easy, however, to unwind portions, as desired. In Fig. 3, the end 11^a of the strip has been unwound from the roll 11 and the diameter of the lower end of the candle accordingly reduced. Fig. 4 shows the portion 11^a torn off and the

operation of reducing the diameter of the lower end of the candle completed.

While I have shown and described certain embodiments of my invention, it is to be understood that it is capable of many modifications. Changes, therefore, in the construction and arrangement may be made without departing from the spirit and scope of my invention as disclosed in the appended claims.

What I regard as new, and desire to secure by Letters Patent, is:

1. A candle having a roll of a strip of flexible sheet material imbedded in its lower end, portions of said strip adapted to be unwound and torn off to reduce the diameter of the lower end of said candle.

2. A candle as claimed in claim 1, in which the strip of flexible sheet material is impregnated with the material of which the candle is made.

In witness whereof, I have hereunto set my hand this 9th day of March, 1931.

MARCUS A. HIRSCHL.
